PARTS STORING CABINET

John A. Belcher, Winnipeg, Manitoba, Canada

Application November 22, 1946, Serial No. 711,551

2 Claims. (Cl. 312—149)

1

In the watchmaking art, the workman is constantly dismantling watches and re-building them with new parts. The majority of these parts are extremely small. Each make of watch has its own parts which are seldom standard with the other makes. Accordingly, the watchmaker, who repairs a large number of makes of watches, is confronted with the difficult problem of storing a multitude of small parts which should be readily accessible.

In the majority of cases, these parts are carried in odds and ends of bottles and boxes with very little system and the result is that endless hours are wasted in hunting for the specified part for some particular watch which the watchmaker knows that he has but does not know just where it has been placed. At times, some of the small parts get mixed with others and the watchmaker cannot tell just which watch they belong to. When such parts are required he has to order them which results in needless delay while the investment in these parts is wasted money.

Under this disorderly arrangement, small parts of various watches tend to get together and the parts that are seldom called for interfere with the finding of those parts which are more often required.

While there are a large number of makes of watches on the market, the standard watches; that is the watches having the largest sale and therefore the majority that come to a watchmaker for repairs, are limited. It is therefore advisable for the watchmaker to keep the parts for these watches in places where they can be readily found, while the few parts, that he may have for watches that are seldom repaired, should be kept segregated.

Further, when watches are left for repair and new parts are ordered, no arrangement is made to inform the watchmaker which watch requires the parts as they come in, unless a bookkeeping system is employed, and so they are usually dropped into the odd bottles or boxes and have to be looked for when the repair is to be done. In the same way, when a large order for parts arrives there is no orderly method of storing or filing said parts for future use. This confusion is aggravated as the business expands and a larger number of watch makes are to be repaired.

The principal object of the present invention is to provide a watchmaker's cabinet with designed containers for systematically storing all the parts for the various makes of watches, in their order, and said containers arranged for ready accessibility by the watchmaker.

2

A further object of the invention is to provide means for listing the various makes of watches in relation to their parts, as stored, so that the watchmaker can quickly find the part required for the particular watch without having to hunt through a lot of other parts.

A further object of the invention is to provide means for storing watches requiring repair when parts have to be ordered and to store said watches in relation to the part containers so that the said watches can be promptly repaired when the parts arrive.

A further object of the invention is to construct the cabinet in sectional units so that it can be enlarged as the watchmaker's business grows, without altering the system.

A further object of the invention is to provide means for quickly re-arranging the listing as the cabinet is enlarged.

A further object of the invention is to construct the containers for removability so that the watchmaker can use them on his desk when repairing a watch or they can all be removed to clean and tidy the cabinet.

A further object of the invention is to provide means on the containers to inform the watchmaker just where said containers are stored in the cabinet so they can be quickly replaced in their proper position.

A further object of the invention is to construct the device such that the watchmaker can observe all the containers at a glance and quickly note which parts are low in stock when ordering supplies.

A further object of the invention is to construct the cabinet and drawers to occupy a minimum of space while giving maximum accessibility to the containers.

A still further object of the invention is to construct the device in a simple, and durable manner and such that it can be placed on the market at a relatively reasonable cost.

With the above important and other minor objects in view which will become more apparent as the description proceeds, the invention consists essentially in the construction and arrangement of parts hereinafter more particularly described, reference being had to the accompanying drawings in which:

50 Figure 1 is a perspective view of one sectional unit of the cabinet showing one drawer out to expose the arrangement of the various containers.

Figure 2 is an enlarged plan view of one of the drawers.

55 Figure 3 is a vertical sectional view taken

through the drawer on the line 3—3, Figure 2.

Figure 4 is a vertical cross sectional view through the drawer taken on the line 4—4, Figure 2.

Figure 5 is a perspective view of one of the boxes for holding train wheels and screws.

Figure 6 is a perspective view of a bracket for holding bottles containing the steel parts, pinions, clocks, and crowns.

Figure 7 is a perspective view of a series of bins for holding main springs.

Figure 8 is a partial perspective view of an extension for the directory plate.

Figure 9 is a face view of one of the index cards.

Figure 10 is a partial sectional view through the cabinet showing the method of aligning the sections.

In the drawings like characters of reference indicate corresponding parts in the several figures.

A section of a cabinet is generally indicated by the numeral 1 in Figure 1. This section is of a low rectangular shape and completely closed except at the front where four openings are provided to receive a similar number of drawers 2. Near the upper corners of the section, circular indents 3 are provided in the upper surface, and the lower surface, in a similar position, is provided with downward extensions 4 which conform to the indents and are received therein when a second section is added underneath.

On the upper surface and at each end of the section a tapped hole is provided to receive a pair of threaded vertical bolt standards 5 and 6 which pass through and support the ends of a directory plate 7, nuts 8 being provided on the standards, above the section to space the said plate therefrom. The front face of the directory is provided with four horizontal series of pockets 9 to receive vertical index cards 10. Each series of pockets is numbered as shown at 11 while along the top of the directory the series of cards are numbered from one to twelve. From the above it will be apparent that when the watchmaker looks at the cabinet the index cards will all be in plain view, each card will belong to one of the four series and each will have a number of its own in the series.

The four drawers belonging to the section are all alike in their contents and so one drawer only will be described. The drawer is of a rectangular shape and may be formed from wood, metal or plastic as desired. A pair of partitions 12 pass centrally across the drawer to divide the drawer into two end compartments 13 and 14 and a central compartment. This central compartment is provided with a horizontal partition 15 which divides the compartment into an upper shallow container 16 and a lower chamber 17 having an entrance 18 at the side of the drawer.

The rear of the front and rear compartments 13 and 14 each receive a bracket 19 (best shown in Figure 6). This bracket is in the shape of a step and is preferably made of metal which encloses a similar shaped piece of wood 20. Six holes are provided in the upper surface of the step and through the wood to form receptacles for a similar number of cork stoppered bottles 21, the upper ends of which extend above the step. Directly in front of the holes, the bracket 19, in compartment 13 is provided with numerals one to six while similarly the bracket in the compartment 14 is provided with numerals seven to twelve so that each bottle has a number to correspond therewith. Each bottle is also provided

with a gummed label having two sets of numbers thereon. The first number will be the number of the bottle and the second one will be the number of the drawer to which it belongs. Behind the holes, each bracket is provided with a holder 22 for the reception of six cards, the cards being positioned directly behind the bottles and are the same size as those on the index plate above the section.

Directly in front of the brackets 19, the compartments 13 and 14 also receive a framework of six bins 23 (best shown in Figure 7). When these bin frames are in position there will be a bin in front of each one of the bottles so that the number in front of the bottles can also be used to designate each one of the bins.

The shallow container in the center of the drawer is designed to receive a series of boxes 24. These boxes are positioned in three rows of four. That is, three boxes across the drawer and four boxes lengthwise of the drawer. The rear wall of each of the boxes is marked with two sets of numbers in the same manner as the bottles and the bins are marked, so that the boxes will be numbered consecutively from one to twelve and have a number corresponding to the number of the drawer to which they belong.

The lower chamber 17 receives a drawer 25 which can be slid out the side when the main drawer is withdrawn from the section. This small drawer is divided by a partition 26 into two compartments 27 and 28. The compartment 28 is empty while the compartment 27 receives a metal covered block of wood 29 which half way fills the compartment. This block, like the bracket 19, is metal covered and is provided with a series of holes to receive relatively small cork stoppered bottles 30. This block carries five lengthwise rows of twelve bottles each, making a total of sixty bottles. The rear wall of the compartment is marked with the numerals one to five so that each one of the five rows of bottles will have a number. The wall of the partition is also marked with a series of numbers from one to twelve to number the rows of bottles in the other direction. In this manner each one of the bottles can be designated by selecting the numbers of the rows in which it is located. In other words, the front left hand corner bottle would be designated by the numerals 1—1. Each of these bottles is provided with a gummed label which is marked with three numbers. The first number would be the number of the longitudinal row, the second number would be the number of the cross row and the third number would be the number of the main drawer in which the bottle belongs. The exposed outer wall of the drawer 25 is provided with a suitable finger grip 31, flush with said wall, so that when the small drawer is slid into the larger drawer said larger drawer may be slid into the section.

The cards 10, shown on the directory 7, and those carried in the holders of the brackets 19, are of the same size and one of them is shown in detail in Figure 9. The name of the watch is printed at the top of the card. The manufacturer's number of the watch is printed on the second line. The size of the watch is printed on the third line and the shape of the watch is printed on the fourth line. When these cards are inserted in the directory they are positioned with the names reading alphabetically therealong. The alphabetical position of the card automatically gives the drawer number and the number for the particular watch parts in the drawer. In

other words, if the card is positioned in the first series the drawer will be number one, if in the second series it will be drawer number two and so on. As there are two sets of numbers from one to twelve at the top of the directory and these numbers are opposite the cards, they indicate the number of the watch parts in the drawer for the make of watch listed on the card. In the same manner, the cards in the drawer are listed to the same grouping.

The main springs for the various watches are placed in the bins 23 having the correct number of the make of catch. The small steel parts, gears, pinions, clicks, and crowns, are carried in the bottles 21 on the brackets 19. Train wheels, and screws are carried in the boxes 24 while the jewels are carried in the small bottles 30 in the side drawer 25. In this connection it may be mentioned that each watch has five important jewels and that is why five lengthwise rows of bottles are provided. Accordingly the numerals one to five not only designate the bottle but also designate a particular jewel while the numerals one to twelve on the drawer partition designate the make of watch. The five jewels referred to are, first the cock jewel, second the foot jewel, third, left pallet stone, fourth, right pallet stone, fifth, roller jewel.

Assuming that all the containers are filled with parts and a watch is to be repaired, the operation will now be described. The watchmaker casts his eye alphabetically along the directory until he finds the name of the watch with the proper information as to manufacturer's number, size and shape. The particular series which the card is in will indicate the drawer number and accordingly he will open that particular drawer. The number above the card will give him the number of the watch parts and as he knows which containers the various parts are in he will accordingly select the container having the correct number and take the part he requires therefrom. By this arrangement the correct part will always be obtained and no mistake can be made.

If several parts are required for a watch, the containers can be removed from the drawer and placed in front of the watchmaker so that he can select them while he works. When the work is finished, the watchmaker will merely look at the containers to observe the numbers and he can then instantly place them in their proper position back in the drawer.

Should a watch come in for repair and the parts required are not in stock, the watchmaker will fasten a card to the watch with the owner's name and the parts required written thereon. The watch will then be placed in the compartment 28 of the small drawer 25. It is important however, that the watchmaker place the watch in the correct drawer having the parts for said watch. He will then order the parts. When these parts arrive and are being placed in their proper containers, the watch will be noted and the card will be read to see if they are the parts required. Accordingly, the repair will be drawn to the watchmaker's attention and will not be overlooked.

By arranging the containers in the order above mentioned it will be noted that the watchmaker has complete visibility of all the containers when the drawers are withdrawn and he can instantly note those containers having no parts therein and those that are becoming depleted. Accordingly, when ordering a fresh supply of parts he

can quickly run his eyes over the drawers to compile his ordering list.

As each drawer will hold all the parts for twelve makes of watches and therefore the four drawers will handle a total of forty-eight makes, one section would give an average small watchmaker a wide coverage of parts and would easily handle most standard makes. If his business grows and he requires a larger coverage, a second section, identical to the first, can be procured. This second section will be placed underneath the first section, the indents 3 registering with the extensions 4 to keep them in line. An extension plate 32 (shown in Figure 8) can then be placed under the directory plate 7, the bolts 5 and 6 being replaced by longer ones. With this addition eight series will be provided for cards instead of four to correspond with the eight drawers. The series on the extension plate will be numbered from five to eight to index the new drawers to the system while the part numbers on the top of the directory plate can still be used for these new drawers as they are aligned with the cards on the extension plate. If the new cards added interfere with the alphabetical arrangement of the cards on the original plate, the said cards can be moved along to make place for the new ones and the parts in the various containers can be changed over to suit. This may take a little time but once done the index system will be correct and such work will not be required again unless another section is added. For most watchmakers, two sections would be ample to take care of the trade.

When filing or storing the jewels in the small bottles, it will be noticed that one watch manufacturer may use the same jewel in several or all models. Obviously, it would be a waste of space to place the same jewel in several different bottles according to the above system. In such cases, the jewels would be placed in a bottle for that particular jewel under the manufacturer's first number. The bottles under the other numbers could then be used for storing cab and plate jewels which the watchmaker may have on hand for that make of watch. The said bottles could also be used to store the extremely small hair spring studs, screws, collets and pins which would be very easily seen in such small bottles. This, of course, is merely a suggestion as to how the space could be utilized to advantage. The watchmaker would no doubt use some such system which would have advantages peculiar to his requirements.

A further advantage of having the closed containers is that several of the small gold filled parts, such as crowns, have a tendency to tarnish and so have to be polished up after assembly. By keeping them in the closed bottles their finish is unmarred thus requiring no polishing and valuable time is saved.

While I have designed and perfected the above described cabinet principally for the watchmaking trade, it will be appreciated that it would have valuable possibilities in other lines such as for the storage of radio, sewing machine, and typewriter or other parts. While I have shown the directory in a vertical position, this was merely to give clear and unobstructed vision to the watchmaker. If desired, however, it may be placed in a slanting position or flat on the top of the cabinet section as long as the index cards are clearly visible for the purpose.

What I claim as my invention is:

1. In a parts storing cabinet: a casing having

a plurality of similar drawers slidable therein; each of said drawers having two vertically spaced partitions passing centrally thereacross and supporting an elevated horizontal partition therebetween to form a visible storage space, when the drawer is open, having a floor of relatively ogee shape from the front to the back of said drawer; and an auxiliary drawer slidable through the side of said first mentioned drawer and receivable in the space below said horizontal partition.

2. In a parts storing cabinet: a section unit having a plurality of similar drawers slidable therein; each of said drawers having two vertical partitions passing centrally thereacross and supporting an elevated horizontal partition therebetween to form a well compartment thereabove, a chamber compartment therebelow and relatively deep compartments at each end of said drawer; a stepped member positioned within and at the rear of each end compartment and provided with a series of vertical holes therealong; bottles mounted in said holes; a series of bins positioned in front of said stepped members; a series of boxes positioned in said well compartment; said bins, bottles and boxes all visible, 25

when said drawer is open, in a relatively ogee formation from the front to the back of said drawer; an auxiliary drawer slidable into the side of said first mentioned drawer and receivable within said chamber compartment; said auxiliary drawer having the bottom thereof provided with plural lines of vertical holes; bottles positioned in said plural lines of holes; the walls of said auxiliary drawer marked to designate said lines of holes; and said bottles and boxes individually marked for the purpose of indicia.

JOHN A. BELCHER.
